UNITED STATES PATENT OFFICE.

EDWIN F. NORTHRUP, OF PRINCETON, NEW JERSEY, ASSIGNOR TO THE AJAX METAL COMPANY, OF PHILADELPHIA, PENNSYLVANIA, A CORPORATION OF PENNSYLVANIA.

PRODUCTION OF CHEMICAL CHANGES BY OSCILLATORY DISCHARGE.

1,297,393.

Specification of Letters Patent. Patented Mar. 18, 1919.

Application filed July 13, 1917. Serial No. 180,288.

To all whom it may concern:

Be it known that I, EDWIN F. NORTHRUP, a citizen of the United States, residing at Princeton, in the county of Mercer and State 5 of New Jersey, have invented a certain new and useful Production of Chemical Changes by Oscillatory Discharge, of which the following is a specification.

The purpose of my invention is to use oscillation current discharge for producing chemical change, which may be either chemical synthesis or chemical dissolution.

A further purpose is to apply to the art of chemical combination or dissociation an 15 agency new to that art for promoting or causing the change.

A further purpose is to provide oscillation current discharge in a substantially closed compartment so that the atmosphere can be controlled and to bring the materials, whether solid, liquid or gaseous, whose combination or dissociation is sought, as close to 20 the discharge gap as possible.

A further purpose is to make a liquid 25 one of the two electrodes between which oscillatory discharge takes place where the liquid is to take part in an intended synthetic combination or chemical dissociation process.

A further purpose is to discharge oscillatory current as close as possible to the surface of a liquid whose elements are to enter into, affect or be subject to chemical change.

A further purpose is to pass an oscillation 35 current discharge between mercury and a solid electrode in the presence of a gas capable of combination with mercury and I illustrate my invention by a special application to the use of air as the "atmosphere" of 40 the gap, and the fixation of nitrogen in atmospheric air.

A further purpose is to perform my operations in an "atmosphere" preferably at or near the atmospheric pressure, where possible, to avoid the difficulty of attaining and maintaining different pressures; contemplating, however, the use of special pressures where the chemical change sought is facilitated by them.

A further purpose is to obtain fixation of 50 atmospheric nitrogen by oscillatory discharge between a solid electrode and a liquid which combines with the nitrogen of the air in the discharge.

A further purpose is to secure abruptness 55 of discharge and high and uniform voltage of discharge in the circuit containing the gap and form as regular impulses as possible.

A further purpose is to utilize the liquid 60 which is to enter into the combination to maintain high uniform voltage of discharge.

A further purpose is to use the favorable characteristics of a mercury discharge gap to standardize and control the discharge impulses even when the discharge utilized for 65 chemical operations does not take place in the presence of the mercury.

Further purposes will appear in the specification and in the claims hereof. 70

I have preferred to illustrate my invention by but three forms thereof, selecting forms which are typical of the use as an electrode of a liquid furnishing part of or catalytically improving chemical operations; 75 discharge between electrodes over or through the surface of such liquid; and discharge in the presence of gases which are to be combined or changed.

Figures 1 and 2 are partly sectional, partly 80 diagrammatic views of two forms of apparatus for carrying out my invention.

Fig. 3 is a fragmentary side elevation showing other forms of apparatus for carrying out my invention. 85

In the drawings similar numerals indicate corresponding parts.

My invention relates both to processes and to the apparatus for carrying them out.

Since my invention may be applied both 90 in synthesis and in dissociation, I shall refer to these generally as chemical changes.

Whether the chemical change is intended to take place in one type of gap illustrated or another, I find it advantageous to maintain a high uniform voltage in the circuit and to prevent maintained arcs between the electrodes. For this reason I show a desirable form of discharge gap in each of my figures, which gap is located within a chamber and automatically maintains this desirable voltage and prevents maintained arcs by shutting off the lower voltage discharges, obtaining the benefit of the high negative electrode resistance of mercury in both directions of impulse travel with the resultant benefit in regulation and a sharp, abrupt, clear discharge. 95 100 105

The form of gap illustrated is not intended to be claimed by me in this application except in connection with the application of its discharge or a discharge affected thereby 5 to effect or assist chemical change, as it is described and claimed by me as a gap in a copending application for discharge gap, Serial No. 175,518, filed June 18, 1917. Its discharge is here valuable for the effect which 10 it produces directly upon substances about it and also because of the strong and steady character of impulse maintained by it in other gaps in circuit with it.

As compared with such a structure as is 15 shown in Swedish Patent No. 24,010 to Mosciki, my invention uses the oscillatory current as the main source of current for producing chemical change.

Describing Fig. 1, then as one form of apparatus and connections by which chemical changes can be brought about through the agency of oscillatory discharge, I show at A A₁ an alternating current supply of any 20 desired phase, here single phase, and which may have any commercial voltage and frequency. I have successfully used a voltage of 220, stepped up to 8,000 or 10,000 volts, at a frequency of 60 cycles.

Where the voltage differs from that desired for charging the condenser in the oscillatory circuit a transformer 5 is used, from whose secondary, in that case, the condenser 6 is charged. It is discharged through a gap 8 and the inductance 7. 30 The discharge gap is used in Fig. 1 for the double purpose of regulating and controlling the character of discharge and of causing the chemical change, here a synthetic change. The desired combination takes 35 place between the liquid electrode used and the "atmosphere" about the discharge.

In this illustration I have shown a much more complicated and refined form of mercury-electrode discharge gap than is required to obtain good oscillations or to combine the mercury with the "atmosphere" chemically; illustrating a common pool for both of the solid electrodes, where independent pools and containers are entirely practicable, showing outside cooling means and supplying other detail which is convenient and desirable but not essential in carrying out even this form of my process.

The cover 10 is important because it makes 55 possible complete control of the "atmosphere" of the gap within the compartment 11, restricts the scattering of the mercury, quiets the gap and prevents undue scattering of the chemical compound formed. The 60 mechanical subdivision and dispersion of the mercury by reason of the disruptive character of the discharge is helpful in increasing the quantity of mercury which is exposed to the action of the discharge.

Both the pot 9 and the cover are desirably

made of material which is electrically non-conducting, of which one of the best materials for the purpose is porcelain.

The solid electrodes 12 are preferably tipped with non-corrosive non-pitting tips 70 13 for which I have found graphite suitable. Any material will serve this purpose which either does not affect the chemical change made or desirably enters into or assists the process.

The solid electrodes are shown as provided with flanges 14 so that they may be rested in place, and as threaded at the tops for nuts 15 by which they may be connected in the circuit.

In order to reduce the danger of short circuiting, the solid electrodes are passed through sleeves 16, likewise preferably of porcelain, or other vitreous material. At the temperature at which such gaps normally operate the mercury scattered by the discharge is dissipated by the surface upon which it falls.

Each of the tips 13 is placed in proximity to a pool of mercury 17, here shown as common to both electrodes. Obviously either of the members may be adjusted to vary the extent of the gap. I prefer to make the mercury level adjustable and for that purpose show a pipe connection 18 by which the mercury may be connected with a pool of mercury capable of bodily vertical movement as disclosed and claimed in the copending application previously referred to.

I show a dropper 19 for the purpose of feeding liquid or vapor into the space 11 about the discharge gaps, by which I may contribute to or retard chemical action or actions or change their character. I may also use the same or another liquid or vapor 105 to reduce the temperature to a desirable temperature of operation.

The outer casing 20 may be spaced from the pot 9 to provide air insulating space merely or to permit the use therein of a 110 liquid or gas supplied from any suitable source, as through pipe 21. The liquid or gas may be used merely for cooling purposes or may be either solely or partially intended to feed gas (including vapor) into 115 the space 11 as shown in Fig. 2, where the outlet 22 may be used merely as a vapor outlet or may feed fluid through inlet pipe 23 and connection 24. An additional inlet 23' may be used to admit air or any solid, liquid 120 or gas desired which cannot be conveniently fed by droppers of the type shown at 19. All of these forms of inlet may be regulated, the regulations for the dropper 19 shown being as a conventional type used in 125 feeding lubricating oil. In the gap shown in Fig. 1, I have successfully tested air, illuminating gas, steam, alcohol, carbon dioxid, water and toluene for various purposes.

I have used ethyl alcohol with great success within the space between the pot and outer casing and have found its vapor desirable in space 11 for cooling purposes. It 5 reduces the quantity of air available for combination with the mercury and, if in sufficient quantity to keep the air out altogether, stops the synthetic combination. Other gases and liquids perform similar 10 functions.

Within a discharge gap of which mercury forms one electrode, both air and steam "atmospheres" combine with the mercury to form desirable compounds. Certain 15 portions of both illuminating gas and alcohol vapor with air may be ignited or exploded by the discharge and this characteristic must be guarded against.

In all oscillation circuits there are two 20 main ways in which energy is dissipated, namely, in the discharge, and in application to the intended use. In the circuits described (Fig. 1) energy is dissipated also in the chemical synthesis which takes place. 25 There is a great increase in efficiency in mercury gaps such as shown in Figs. 1 and 2 where alcohol vapor displaces substantially all of the air in the chamber 11 as compared with the efficiency where the gap 30 is surrounded by air. Where the alcohol vapor is used almost no synthetic chemical change takes place, contrasting with considerable chemical change when air is freely admitted. Though part of the increase in 35 efficiency with alcohol vapor is due to beneficial cooling of the gap by the alcohol a considerable part of the efficiency increase is due to the saving of the energy expended in synthetic chemical change where the "atmosphere" is air.

In Fig. 2 in conjunction with my preferred discharge gap for maintaining high and uniform voltage of discharge and sharp, regular rupture of the circuit, I have shown 45 a supplemental discharge gap intended for synthetic chemical operations or dissociation of chemical compounds alone, using some other liquid as the electrode. The pot 25 is provided with a closure 26 so that the atmosphere within may be controlled and undue scattering of the liquid and of the chemical compounds produced may be prevented. The interior 27 may contain any suitable gas or gases or liquid above the liquid electrode. 50 A solid electrode 28, joined to the circuit at 29 is supported by the cover and insulated therefrom, as at 30, permitting the use of an electrically conducting material for the pot and cover, where desired. Porcelain or 55 similar non-conducting material having a vitreous surface would be advantageous here also.

The lower part of the pot is shown as holding a liquid electrode. The liquid or liquids 60 and the atmosphere will be selected with a

view to the chemical operation which is to be performed. I have shown a pipe 32 by which the liquid may be conveniently and regularly fed into the pot and by which its height and the spacing of the gap between 70 the electrodes, may be controlled either by a supplemental container of adjustable height or by other means. The gap is here adjustable by screwing the solid electrode up or down.

In the discharge gap 8, in Fig. 2 I show a liquid 38 floating on the surface of the mercury and dispersed by the discharge. It illustrates the use of two liquids with or without surrounding special atmosphere. 80 The two liquids can thus be chemically changed, as, for example, by being made to combine or combined with the atmosphere; or a lighter liquid may be finely distributed in and combined with an atmosphere with 85 which the liquid electrode will not combine, or may be dissociated. I have dissociated water in this way, both by floating it upon a mercury electrode, and by using it as an electrode.

In Fig. 3, the same kind of mercury gap 8 is placed in series with two differently used gaps to regulate and steady their discharges. Switch mechanism permits either or both of the supplemental gap devices 33 95 and 33' to be cut out of the circuit. Here again, another gap could be used instead of the one shown by me at 8, though with less advantage, and the use of any additional gap at 8 may be avoided where the character 100 of the other gap or gaps used for the chemical operation sufficiently controls and maintains the voltage, character and rate of discharge required to accomplish the change sought. I believe that superior results are 105 attained by using a mercury gap and that some chemical combinations or dissociations are rendered easy by it which would be difficult if not impossible, without the control of the voltage and the abruptness and regularity of discharge due to using the high negative electrode resistance of mercury.

In the gaps shown at 33 and 33' I provide solid electrodes 34 and 35, 36 and 37 between which the discharge takes place. In the gap 33 the discharge is arranged in suitable proximity to a liquid 38', intended to coöperate in the synthetic chemical combination to be formed or itself to be dissociated. The "atmosphere" at 39 about the discharge may 115 be gas or vapor and a lighter liquid 38² may also be used. Obviously also, the presence of any of the liquids used by me may be desirable for catalytic coöperation alone.

In the device shown at 33', no liquid is indicated and the synthetic change is intended to be effected between or within gases or vapors alone.

In all my forms solid matter, preferably 120 finely divided, and any fluid, whether liquid, 130

gas or vapor or any mixture of these may be inserted through one or other of the inlets shown generically at 18, 19, 23' and 32, as may be required for the several operations.

- 5 The portion of the circuit shown in Fig. 3 is intended to be connected with any desired oscillation circuit and may be connected with such a feeding circuit as shown in Figs. 1 and 2 by connecting the wires 40, 41 10 thereof to the remainder of the circuit at the points 40', 41' in these figures.

The devices shown in Fig. 3, connected in series for convenience of illustration, may be so used. In order to show their capability 15 of independent use, I have illustrated jumpers 42, provided with switches 43 by which either or both of these may be cut out.

In operation, with the form shown in Fig. 1, when there is free access of air, the discharge causes the mercury to combine with the nitrogen and oxygen of the air, separately, forming a dark gray, almost black powder comprising a mixture of nitrate of mercury, $Hg_2(NO_3)_2$, and the gray sub-oxid 25 of mercury, Hg_2O . By the application of gentle heat, the nitrate of mercury is made to yield NO_2 , which, passed through water, gives nitric acid and the mercury is also released from the oxygen, making the operation cyclic, so far as the mercury is concerned, in that all of the mercury is recovered.

The cooling use of vapor, as for example, alcohol vapor, about the gap, reduces the entire quantity of air present and consequently reduces the extent both of desirable production of mercuric nitrate and of the undesirable production of mercuric oxid. However, the formation of the undesirable 40 sub-oxid of mercury may be reduced to advantage, without reducing the quantity of the mercuric nitrate by reducing the proportion of oxygen in the air. This may be done by passing the air over hot coke, through the 45 fractional distillation of liquid air, or by other well-known ways.

I have considered the use of air as the "atmosphere" for the application of my invention to fixation of nitrogen because of the 50 cheapness and ease of handling air even when it is desirable to reduce its oxygen content before use, and because of the desirable operation of both the gap described and my process, herein claimed, at atmospheric pressures.

Obviously, my invention will apply also to other mechanical mixtures of nitrogen, provided injurious gases be not present to sufficient extent to interfere with the combination sought. It is applicable also with pure nitrogen at atmospheric temperatures. As I have indicated at another point in regard to other gases, the adaptability of my invention to use with gases at atmospheric pressures is viewed by me as a con-

siderable advantage but not as requiring that atmospheric pressures shall be used. Nor do I purpose restricting my invention to particular temperatures for the materials supplied in proximity to the gap nor for 70 the gap.

Having thus described my invention, what I claim as new and desire to secure by Letters Patent is:—

1. The combination of an oscillatory discharge comprising the main agent for producing chemical change, a container within which the discharge is located and different materials within the container and in proximity to the discharge adapted to be chemically changed by reason of the discharge. 75

2. Apparatus for chemical synthesis comprising a container, a solid electrode and a fluid electrode therein and a gas or vapor surrounding the electrodes and with which the fluid electrode will coöperate in the production of chemical compounds in combination with a source of high frequency electrical supply, applied across the space between the electrodes to produce the chemical 80 union. 85

3. Apparatus for chemical synthesis comprising a container, a solid electrode and a mercury electrode therein and air about the electrodes having a low oxygen content as 95 compared to the nitrogen present in combination with a source of high frequency electrical supply, for causing the mercury and nitrogen to combine.

4. Apparatus for chemical synthesis comprising a solid electrode, a mercury electrode in proximity thereto, a container therefor admitting air in combination with a source of high frequency electrical supply, crossing the gap between the electrodes for causing 100 the mercury to combine with the nitrogen 105 of the air.

5. Apparatus for effecting chemical changes comprising a mercury discharge gap, a second gap in series therewith and material to be chemically changed in proximity to the second gap. 110

6. Apparatus for effecting chemical change comprising an oscillation discharge gap, a casing thereabout, within which the 115 material to be treated may be acted upon and a second oscillation discharge gap giving character to the discharges in the circuit.

7. In apparatus for chemical synthesis, 120 discharge gap electrodes and a plurality of fluids in proximity to the gap.

8. A pair of oscillation discharge gaps in series, one maintaining a high voltage of discharge and the other effecting chemical 125 changes.

9. A pair of oscillation discharge gaps in series, one producing strong and steady oscillations and the other applying the oscillations to effect chemical change. 130

10. The process of fixation of nitrogen which consists in discharging an oscillatory current across a gap between a solid electrode and mercury in the presence of air.
- 5 11. The process of fixation of nitrogen which consists in removing a portion of the oxygen from air and discharging an oscillatory current across a gap between a solid electrode and mercury in the presence of air 70 so reduced in oxygen.
- 10 12. The process of fixation of nitrogen which consists in discharging an oscillatory current across a gap from or to a mercury electrode in the presence of a gas rich in uncombined nitrogen.
- 15 13. The process of fixation of nitrogen which consists in combining mercury and free nitrogen by means of electrostatic discharge.
- 20 14. The process of fixation of nitrogen which consists in discharging an oscillatory current across a gap between a solid electrode and mercury in the presence of a mixture of air and another gas.
- 25 15. The process of fixation of nitrogen which consists in discharging an oscillatory current across a gap between a solid electrode and mercury in the presence of air and concurrently cooling the gap.
- 30 16. The process of fixation of nitrogen which consists in discharging an oscillatory current across a gap between a solid electrode and mercury in the presence of air and using alcohol to reduce the temperature.
- 35 17. The process of synthetic fixation of nitrogen which consists in producing mercury nitrogen compound by the passage of oscillatory current between mercury and a solid electrode in the presence of air to cause 100 union between the mercury and the nitrogen of the air and subsequently heating the mercuric nitrate.
- 40 18. The process which consists in passing an oscillatory current between mercury and a solid electrode in the presence of air to cause the mercury to combine separately with the nitrogen and with the oxygen of the air.
- 45 19. The process which consists in passing an oscillatory current between mercury and a solid electrode in the presence of air to produce combinations of mercury with nitrogen and with oxygen respectively and subsequently heating the resultant combinations to cause the evolution of nitric oxide, combining it with water to form nitric acid, and returning the mercury to liquid form.
- 50 20. The process of production of nitric acid which consists in passing oscillatory electric current between mercury and a solid electrode in the presence of air to produce 110 nitrate of mercury and subsequently treating the resultant compound to produce nitric oxide and nitric acid, successively and to recover the mercury.
- 55 21. In the process of production of fixed nitrogen by passing an oscillatory electric current across a mercury and solid discharge gap producing mercuric nitrate and a mercury sub-oxid, the step which consists in preliminarily removing oxygen from the air 75 about the gap.
22. The process of fixation of nitrogen which consists in the formation of a compound between mercury and nitrogen by passing oscillatory electric discharge across a gap between mercury and a solid electrode in the presence of nitrogen.
23. The process of fixation of nitrogen which consists in producing a mercury compound with nitrogen and a mercury compound with oxygen concurrently by the passage of an oscillatory current between mercury and a solid electrode.
24. The process of fixation of nitrogen which consists in producing a mercury compound with nitrogen and a mercury compound with oxygen concurrently by the passage of an oscillatory current between mercury and a solid electrode in the presence of air and relatively reducing the quantity 90 of the mercury compound with oxygen by reducing the oxygen content of the air.
25. The process of producing chemical change by the action of an oscillation discharge which consists in maintaining strong 95 and steady oscillations by a discharge gap separate from the gap in which the chemical change is effected but in series in the same circuit with it.
26. The process of producing chemical 100 change which consists in passing an oscillatory discharge through a liquid to disperse the latter and at the same time subject it to the action of the discharge.
27. The process of producing chemical 105 change which consists in passing an oscillatory current comprising the main agent for producing chemical change, across a gap in the presence of the material to be dissociated.
28. The process of producing chemical 110 synthesis which consists in passing an oscillatory current comprising the main agent for producing chemical change, across a gap in the presence of materials to be chemically 115 combined.
29. The process of producing chemical synthesis which consists in passing an oscillatory current across a gap in the presence of fluid intended to enter into the synthetic 120 combination and above the surface of a liquid adapted to affect the combination formed.
30. The process of producing chemical 125 synthesis which consists in passing an oscillatory current across a gap in the presence of a plurality of gases adapted to enter into chemical combination, thereby bringing about the combination.
31. The process of producing chemical 130

- synthesis which consists in uniting fluids in chemical compounds by the production of an oscillatory discharge in the presence of the fluids.
- 5 32. The process of producing chemical synthesis which consists in uniting a liquid and a gas by producing an electrical discharge above the surface of the liquid in the presence of the gas.
- 10 33. The process of producing chemical synthesis which consists in uniting a liquid and a gas by producing an electrical discharge above the surface of the liquid in the presence of the gas and utilizing the liquid 15 as one of the electrodes for the discharge.
34. The process of producing chemical synthesis which consists in subjecting to an oscillatory discharge comprising the main agent for producing chemical change, a plu-
- rality of materials which affect the character of a synthetic combination to be formed.
35. The process of producing chemical synthesis which consists in subjecting to an oscillatory discharge the materials to be combined contained in one discharge-gap 25 vessel connected in series with another discharge gap capable of producing and maintaining strong and steady electrical oscillations.
36. The process of producing chemical 30 change which consists in exposing a chemical combination to the effect of an oscillation current discharge comprising the main agent for producing chemical change, for the purpose of breaking the combination up 35 into other combinations or its constituent parts.

EDWIN F. NORTHRUP.
